Inventor:

Oscar M. Andrews

UNITED STATES PATENT OFFICE.

OSCAR M. ANDREWS, OF HECLA WORKS, NEW YORK, ASSIGNOR TO A. K. SEYMOUR, OF SAME PLACE.

BLIND-FASTENER.

Specification of Letters Patent No. 26,319, dated November 29, 1859.

To all whom it may concern:

Be it known that I, OSCAR M. ANDREWS, of Hecla Works, in the county of Oneida and State of New York, have invented a new and 5 Improved Blind-Fastener; and I do hereby declare that the following is a full, clear, and exact description of the same, reference being had to the accompanying drawings, forming a part of this specification, in 10 which—

Figure 1, represents a transverse vertical section of the frame of a blind, the blind or shutter being open and fastened according to my invention. Fig. 2, is a horizontal 15 section of the same. Figs. 3 and 4, are similar views to Figs. 1 and 2, respectively, representing a modification of my invention.

Similar letters of reference indicate corresponding parts in the several figures.

20 The object of this invention is to fasten a blind or shutter, when the same is open, in such a manner, that the fastening can be reached without sticking the head and body away out of the window, and my invention 25 consists in arranging on that side of the frame to which the blind or shutter is hinged, a rotary cam of particular construction, that catches into a hook formed by that part of the butt hinge, which is secured to the blind 30 or by a separate piece secured to the blind in any convenient place.

To enable those skilled in the art to make and use my invention I will proceed to describe it.

35 The shutter or blind A, is attached to the frame B, by means of hinges C, C', in the usual manner. The upper hinge C', is constructed precisely like the hinges which are now in general use, but that part of the 40 lower hinge C, which is secured to the shutter, is furnished with a hook a, that catches over a cam D, which is attached to the side of the frame B. The cam D, is wedge shaped so that it forces the blind or shutter 45 up against the wall and it rotates on a pivot b, in a casing c, which is mortised into or otherwise rigidly attached to the side of the

frame. The front part of said cam is so heavy that the same by reason of its own gravity is always kept in the proper position to catch over the hook a, and the inner side of the hook a, forms an inclined plane, so that when the blind or shutter is thrown open the cam slides up said inclined plane and catches over the hook as soon as the 55 shutter has reached its extreme position close up to the wall. A lug or handle e, serves to raise the cam so as to allow the shutter being closed and a stop f, prevents said cam being drawn back too far so that the same by 60 reason of the superior gravity of its front end sinks down again ready to catch over the hook, as soon as the hand relaxes.

Instead of attaching the hook a, to a part of the hinge, a separate hook a', may be secured to any convenient place on the shutter between the hinges, as clearly shown in Figs. 3 and 4. The form of the hook a', is similar to the hook a, its inner end forming an inclined plane, causing it to raise the cam 70 when the shutter is opened and to catch behind the hook when the shutter has reached its extreme position close up to the wall. In either case the shutter can be opened by pushing it back as usual and it can be closed 75 by raising the cam D, and pulling the blind or shutter in, all of which can be done by raising the window but little and thrusting the arm out just far enough to reach the cam and to pull the shutter in.

Having thus fully described my invention what I claim as new, and desire to secure by Letters Patent, is—

Arranging on the side of the frame B, of a shutter or blind A, a rotary wedge-shaped 85 cam D, in combination with a hook a, or its equivalent fastened to the shutter substantially in the manner and for the purpose specified.

OSCAR M. ANDREWS.
